US0D1112741S

(12) **United States Design Patent** (10) **Patent No.:** **US D1,112,741 S**
(45) **Date of Patent:** **** Feb. 10, 2026**

(54) **TIBIAL BASEPLATE**

(71) Applicant: **MAKO Surgical Corp.**, Weston, FL (US)

(72) Inventors: **Ron Irwin**, Stuart, FL (US); **Ali Abbasi**, Davie, FL (US); **Mark Nadzadi**, Memphis, TN (US); **Jason Otto**, Plantation, FL (US); **Tom Coon**, Redding, CA (US); **Ken Gustke**, Weston, FL (US); **Richard Illgen**, Weston, FL (US); **Stefan Kreuzer**, Weston, FL (US); **Carlos Lavernia**, Coral Gables, FL (US); **Martin Roche**, Ft. Lauderdale, FL (US); **Harry Rubash**, Weston, FL (US)

(73) Assignee: **MAKO Surgical Corp.**, Weston, FL (US)

(**) Term: **15 Years**

(21) Appl. No.: **29/846,367**

(22) Filed: **Jul. 15, 2022**

CLAIM

The ornamental design for a tibial baseplate as shown and described.

DESCRIPTION

FIG. 1 is a perspective view of a tibial baseplate showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front perspective view thereof.

The broken lines in the drawings illustrate portions of the tibial baseplate that form no part of the claimed design.

1 Claim, 5 Drawing Sheets

Related U.S. Application Data

division of application No. 29/544,882, filed on Nov. 6, 2015, now Pat. No. Des. 841,810, which is a division of application No. 29/466,144, filed on Sep. 4, 2013, now Pat. No. Des. 744,103, which is a continuation-in-part of application No. 13/340,636, filed on Dec. 29, 2011, now Pat. No. 9,649,195, and a continuation-in-part of application No. 13/340,645, filed on Dec. 29, 2011, now Pat. No. 8,911,501.
